METHOD OF AND MACHINE FOR FORMING LININGS

Willis P. Drew, La Grange, Ill., assignor to Arkell Safety Bag Company, New York, N. Y., a corporation of New York

Application September 10, 1947, Serial No. 773,264

4 Claims. (Cl. 93—8)

1

The present invention relates to methods of and machines for forming linings, bags, and other articles made of stretchable paper, and has for its object to provide a novel and improved method and machine of this character.

The several features of the invention, whereby this and other objects may be attained, will be readily understood from the following description and accompanying drawings, in which:

Figure 1 is a view in perspective of a bag lining embodying the features of the invention in their preferred form;

Figs. 2 and 3 are detail sectional views, on an enlarged scale, respectively taken on the lines 2—2 and 3—3 of Fig. 1;

Fig. 4 is a top end view of the lining shown open and ready for use;

Fig. 5 is a view in perspective of a modified form of lining;

Fig. 6 is a similar view of another modified form of lining;

Fig. 7 is a view in perspective of a drop or covering sheet made in accordance with my improved method, the sheet being shown in dotted lines in open or spread condition;

Fig. 8 is a diagrammatical side view of a machine that may be employed in carrying out my improved method; and

Fig. 9 is a diagrammatical plan view of the same.

In forming linings of the construction illustrated in Figs. 1 to 4, two webs of plain or flat paper 2 and 4, such as kraft paper, are fed longitudinally in superposed relation from supply rolls 6 and 8 (Figs. 8 and 9), the webs being brought together as they pass over a roller 10. As the two webs approach the roller 10, transverse strips of adhesive 12 may be applied to the underside of the web 4 as by means of a rotating blade 14 which receives glue from a glue roll 15, the strips of glue 12 being spaced apart a distance corresponding substantially to the length of the linings to be formed. These transverse strips of adhesive 12, however, may be omitted in certain instances as hereinafter described.

As the webs 2 and 4 approach the roller 10, strips of adhesive 16 are applied to the underside of the longitudinal margins of the web 4 by means of glue rolls 18. Thus as the webs 2 and 4 pass over roller 10, they are secured together at the transverse strip portions 12 and the longitudinal marginal portions 16.

As the two webs approach the roller 10, saturated steam from a pipe 19 is blown under pres-

2

sure between the converging webs to moisten their inside surfaces to assist in preparing the sheets for crinkling, the steam striking the sheets about two inches from the roller 10.

From the roller 10 the composite strip thus formed passes over a guide roller 20 and beneath a perforated drum or screen 22 in a water tank 24 so as to moisten the composite strip. It will be understood, however, that any other suitable means may be employed to moisten the strip. When the strip thus receives the proper amount of moisture, it may pass through a crinkling and corrugating machine, indicated at 26. This machine may be and preferably is the same as the one illustrated and described in the patent to McBean 2,124,582, dated July 26, 1938. This machine applies transversely extending crinkles 28 and corrugations 30 to the composite web, the corrugations being somewhat flattened in a more or less dove-tailed form.

After leaving the crinkling and corrugating machine, the web may be passed through a drier 27 having rollers or tubes 29 over which the web passes as it travels back and forth through the drier. As the web leaves the drier it passes between nip rolls 31 which may pull the web into festooning apparatus (not shown) for loading trucks.

Subsequently the web may be severed on lines 30 12 as by means of knives 33. In case the transverse strips are omitted, lining or bag tube lengths may be formed upon severing the web on lines that are properly spaced apart.

In cases where the transverse strips 12 have been omitted, it has been found that the composite web or tube comes out of the drier in a balloon-like manner rather than in a flat form. This results in the sheets, in spite of the previously formed interlocking crinkles and corrugations, being separated throughout the entire area thereof between the longitudinal lines of adhesive. Consequently when each bag tube length is cut off, the two sheets or walls thereof are not attached together by interlocking of the corrugations between the lines of adhesive, but are separated so that the bag tube, either before or after it is made into a lining may be easily opened.

I have found that in case of any gap or leakage in the side seams, such ballooning effect is eliminated or reduced until the defective portion passes the nip rolls. In this way any such defect in the bag lengths or linings can be easily

detected previously to completing the bags or linings.

The reasons for such ballooning of the composite web or tube and separation of the sheets are believed to be as follows: The blowing of saturated steam under pressure between the two webs as they approach the roll 10 by means of the pipe 19 as described, results in a constant pressure at this point of steam and air. The subsequent processing of the sheets in crinkling and corrugating, is done against this pressure although the volume of entrapped air and steam at this point is small. The tube enters the drier wet, and at this point it is practically flat since the corrugations tend to hold the top and bottom sheets together. As the tube travels through the drier the heat tends to expand the entrapped air and gas and gradually a small ballooning effect is noticeable. When the tube leaves the final roll of the drier and is fed between the two nip rolls 31, the nip rolls restrain the passage of air between them and as a result the entrapped air and gas is forced back into the space between the drier and the nip rolls. Also the rows of the drying rolls or tubes in the drier hold the paper tightly, thus preventing the pressure built up at the nip rolls from passing back materially into the paper in the drier. This results in a section of the paper tube being held together at both ends, and as they are sealed airtight at both edges, ballooning out under pressure built up is effected.

I have found that the degree of ballooning may be effected by the porosity of the paper, the amount of steam pressure applied before crinkling, the smoothness of the finish of the surface of the paper, the amount of cross direction stretch, the degree of waxing applied to the two sheets, and the amount that the corrugations are flattened previously to passing through the drier. Also, the degree of ballooning may be varied within certain limits by adjustment of the nip rolls.

In case the sheets of the web are secured together by transverse lines of adhesive 12, the ballooning is effected as the web leaves the drier between said lines of adhesive.

It has been a serious problem to form satisfactory pasted seams in linings in the case of crinkled or crinkled and corrugated paper. With the present method, however, by first applying the paste and thereafter crinkling and corrugating, preferably before the paste has become dry, an exceptionally strong and tight seam is provided. Also, the seams as thus formed are capable of elastic stretchability under strain especially when the adhesive is somewhat elastic. The adhesive is preferably waterproof but in certain instances owing to the speed of operation of the machine that is unnecessary in spite of the moistening of the paper previously to crinkling. As the walls of the lining are crinkled and corrugated together they are of uniform stretchability and capable of uniformly resisting bursting strains. After the two webs are sealed together at the seams, and previously to crinkling and corrugating, the seams may be passed through a paraffin bath which applies a protective coating to the seams, or the entire sealed webs may be passed through the bath so as to moistureproof them throughout.

Instead of forming a single tube as described, by increasing the number of longitudinal strips of adhesive, for example from two to four or six, a plurality of tube lengths may be formed, across

the width of the webs, and the several tubes separated by slitting the webs longitudinally after crinkling and corrugating.

In the form illustrated in Fig. 5, instead of the longitudinal margins being secured together in the plane of the sheets as in Fig. 1, the sheets are arranged in overlapping relation with the projecting longitudinal margin 32 of each sheet folded over and adhesively secured to the other sheet. When the margins are thus folded and adhesively secured, the composite sheet is then ready to be acted upon by the crinkling and corrugating mechanism.

Instead of the bottom of the lining being closed by a transverse strip of adhesive 12 as in the case of the form shown in Fig. 1, the bottom may be closed by sewing or by folding over one end margin 34 and securing it by means of a line of stitching 35 (Fig. 5).

In the form shown in Fig. 6 the walls of the bag are made up of two strips of different widths with the margins of the wider strip 36 folded over and pasted to the margins of the narrower strip. It will be noted that in the forms shown in both Figs. 5 and 6 when the composite web is run through the crinkling and corrugating machine exceptionally strong seams are formed.

The drop or covering sheet illustrated in Fig. 7, is made from two or more webs 38 and 40 which may be moisture-proofed. Previously to crinkling and corrugating these webs, corresponding margins thereof are secured together by a line of adhesive 42, or a folded seam may be formed such as shown in Figs. 5 and 6. After thus securing the webs together they are run through the crinkling and corrugating machine so as to form a composite crinkled and corrugated web. Parts of the corrugated web may then be separated except for the secured marginal portions 42 so as to form a single sheet.

Crinkling and corrugating machines such as that of said McBean patent at present in use are capable of crinkling and corrugating sheets of not more than eighty to one hundred inches in width, and it has been a serious problem to provide a sheet of greater width, such as is frequently desired for covering purposes or drop sheets for painters' use. In accordance with my improved method a covering sheet may be made of substantially twice or several times the width of the usual crinkled and corrugated sheet.

It will be apparent that my improved method may be carried out expeditiously and inexpensively in producing my improved material, bag or lining and covering sheet, and that uniform results are insured. Also, that my improved machine is simple in construction and efficient in operation.

While the material is preferably made stretchable by crinkling and corrugating, in certain instances it may be made stretchable by other means, and for certain uses may be made stretchable in but one direction. For convenience of illustration, while the linings are shown of short length, bag linings are usually made of substantially greater length than width.

As will be evident to those skilled in the art, my invention permits various modifications without departing from the spirit thereof or the scope of the appended claims.

What I claim is:

1. The method of making articles of manufacture of the class described which comprises feeding two webs of paper longitudinally and positioning them together at a predetermined

point as they are being fed, applying adhesive to the webs so as to cause their longitudinal margins to be secured together, directing saturated steam under pressure between the webs at the point where they are brought together forming gatherings in the composite web to provide for stretchability in at least one direction, and applying heat to the web to cause ballooning thereof due to the expansion of the air and moisture between the sheets of the web.

2. The method of making articles of manufacture of the class described which comprises feeding two webs of paper longitudinally and positioning them together at a predetermined point as they are being fed, applying adhesive to the webs so as to cause their longitudinal margins to be secured together, applying saturated steam under pressure between the webs at said point in their travel, passing the composite web through a liquid bath to cause moistening thereof, crinkling the moistened web so as to provide for longitudinal stretchability and corrugating it so as to provide for transverse stretchability, passing the web through a drier, and as it leaves the drier passing it between nip rolls whereby ballooning of the sheets of the web between the longitudinally secured margins thereof is effected.

3. In an apparatus for making articles of the class described, the combination of means for feeding two webs of paper longitudinally and positioning them together one upon the other at a predetermined point in their travel, devices for adhesively securing together the longitudinal margins of the webs as the webs are being fed, means for directing saturated steam under pressure between the webs at said point where they are positioned together, a liquid bath through which the composite web passes for moistening the web, means for forming gatherings in the

moistened web to provide for stretchability in at least one direction, and a drying device for drying the web after it leaves the last mentioned means and for causing ballooning thereof.

- 5 4. The method of making an article of manufacture of the class described, which comprises feeding two webs of paper longitudinally and positioning them together at a predetermined point as they are being fed, applying adhesive to the webs so as to cause their longitudinal margins to be secured together, spraying moisture under pressure between the webs at the point where they are brought together, passing the composite web through a liquid bath to cause moistening thereof, forming gatherings in the moistened web to provide for stretchability in at least one direction, and passing the web through a drying device for drying the web and for causing ballooning thereof due to the expansion of the air and moisture between the sheets of the web.
